ELECTRICAL THERAPEUTIC DEVICE

Filed Dec. 5, 1922.

Inventor.
Samuel E. Peden

UNITED STATES PATENT OFFICE.

SAMUEL E. PEDEN, OF ST. LOUIS, MISSOURI.

ELECTRICAL THERAPEUTIC DEVICE

Application filed December 5, 1922. Serial No. 605,141.

To all whom it may concern:

Be it known that I, SAMUEL E. PEDEN, a citizen of the United States, residing in the city of St. Louis and State of Missouri, have invented certain new and useful Improvements in Electrical Therapeutic Devices, of which the following is a specification.

This invention relates to an electrical therapeutic device, and has for its object to provide in a manner as hereinafter referred to, a device of such class having means whereby the device can be employed as a cauter, or for stimulating granulations, or for the destruction of bacteria, and further whereby the device is so set up as to enable the employment thereof for the treating of patients without the necessity of their removal from their homes, and to further provide a device so arranged that the light projected therefrom is accessible to the many orifices of the body of the patient as to make direct application possible.

Further objects of the invention are to provide an electrical therapeutic device which is simple in its construction and arrangement, strong, durable, compact, portable, thoroughly efficient and convenient in its use, readily assembled and comparatively inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a perspective view of an electrical therapeutic device in accordance with this invention, showing the use thereof in connection with a patient.

Figure 2 is a longitudinal sectional view. Referring to the drawings in detail, an electrical therapeutic device in accordance with this invention includes a supporting element in the form of a tripod embodying a plurality of supporting legs, as indicated at 1, 2 and 3, and each of which is hinged at its upper end as at 4, to a collar 5, pro-

vided with a set screw 6. Hinged brace members 7 are connected with the supporting legs and also with a supporting member 8. The brace members 7, legs 1, 2 and 3 and supporting member 8, are so set up relatively to each other that this tripod can be folded when desired.

Adjustably connected to the collar 5, through the medium of the screw 6, is a vertically disposed standard 9, having its upper end provided with a set screw 10, and extending into the upper end of the standard 9, is the vertical leg 11 of a vertically adjustable angle-shaped hanger member having the horizontal arm 12. The hanger member is maintained in its adjusted position by the set screw 10. The horizontal leg 12, of the hanger member has its free end provided with a hook 13.

The device further includes a lamp element consisting of a hollow cylindrical body portion 14, forming a light chamber 15, and which is closed at its rear end by a perforated removable closure 16, and has mounted in its forward end a flat annulus 17 having its inner end inset as at 18, to extend into the chamber 15. The cylindrical body portion 14, is flanged as at 19, so as to overlap the annulus 17. The annulus 17, has projecting outwardly therefrom a collar 20, which surrounds the inner edge of the annulus 17, and the function of the collar 20 will be presently referred to.

The cylindrical body portion 14, in proximity to the rear thereof, at diametrically opposite points is provided with openings 21, 22. Extending through the opening 21, as well as secured to the body portion 14, is a flanged coupling member 23, and extending through the opening 22, as well as being secured with the body portion 14, is a flanged coupling member 24. Extending through the coupling member 23, as well as being pivotally connected therewith, as at 25, is a downwardly inclined carbon holder 26, which extends toward the front of the body portion 14, and extending through the member 24, as well as being fixedly connected therewith, is an upwardly inclined carbon holder 27, which projects toward the carbon holder 26, and toward the front end of the body portion 14. Mounted in the holder 26, is a carbon 28, and mounted in the holder 27 is a carbon 29. Electrically connected with the holder 26 and carbon 28, is a circuit wire 30, and electrically con-

nected with the holder 27 and carbon 29 is a circuit wire 31.

Mounted on the body portion 14, is a magnetic device or solenoid 32, which is electrically connected as at 33, with the holder 26 and carbon 28, and which has the core thereof electrically connected with the holder 26, by a shifting element 33^a, the function of which is to elevate the holder 26 and carbon 28, for a purpose to be presently referred to.

Mounted on the supporting member 8, as well as surrounding the lower end of the standard 9, is a resistance element 34, provided with a pair of leading-in wires 35, carrying a plug 36 so that the device can be connected with a source of electrical energy when occasion requires.

The body portion 14, forwardly of the solenoid 32, is provided immediately above the arc formed by the carbons 28, 29, with an air vent 37.

Mounted on the collar 20, and projecting forwardly therefrom is a light directing tube 38. Mounted in the collar 21, in proximity to the light opening 39, formed by the annulus 17, is a concavo-convex lens 40, and arranged within the tube 38, forwardly of the lens 40, is a lens holder 41, provided with a concavo-convex colored lens 42. Positioned in the forward end of the tube 38, is a lens holder 43, provided with a biconvex lens 44.

The body portion 14, at its forward end, has projecting therefrom, a combined coupling and guide member 45, through which extends a suspension chain 46, which is connected around the tube 38, for the purpose of suspending the latter. The chain 46, has a link 47, detachably mounted in the hooked end 13 of the horizontal leg 12, of the hanger member.

The light is produced by the carbons 28 and 29, which are disposed at an inclination and point toward the lens 40, in such a manner as to avoid casting a shadow over the field to be treated, and the carbons are used because they produce a complete spectrum and the light at the arc is condensed by the lens 40 to a perfect focus. The arc is created through the medium of the solenoid 32, which, when the current is on, lifts the carbon 28 to a given height and holds it fixed, as shown in Figure 2. The carbon holder 27, is properly insulated and is in a fixed position. The carbon holder 26, is also properly insulated, but is shiftably supported owing to the pivotal mounting thereof.

Preferably the material from which the lamp is constructed is nickel plated copper, and the lenses are so positioned that the focus will be about three feet from the lamp. The lenses 40 and 42 have a meniscus with a nine and one-half inch focus, and are so

positioned in the tube 38, so that the convex surfaces are away from the arc, preferably a distance of about six inches apart, and with the proximal lens 40 about four inches from the arc. The tube and lenses 70 are easily removed for cleansing purposes. The lens 42, is positioned within the tube in such a way as to be supported from one side, and the lens holder 43 retains it in place. The holder 43, carries the bi-convex lens 44; the latter is encased in a copper band and this bi-convex lens 44, shortens and intensifies the light rays so that they can be used as a cautery.

The employment of the chain 26 provides a balancing means and enables the lamp to be easily manipulated.

The hanger element as it is adjustably connected to the standard 9, permits the lamp to be swung at any desired position 85 or to be adjusted to any desired height, and owing to the employment of the resistance 34, it eliminates the surge of the current as it leaps from one carbon to the other.

From the foregoing description taken 90 in connection with the accompanying drawings, a therapeutic device is set up, whereby the light rays therefrom can be utilized as a cautery, or to stimulate granulations, or for the destruction of bacteria, and although 95 the preferred embodiment is as shown, yet it is to be understood that changes in the details of construction can be had without departing from the spirit of the invention as claimed.

What I claim is:

1. A therapeutic device comprising a light casing provided with a light directing tube, inclined carbon holders projecting into said casing, circuit connections leading to said holders, carbons carried by said holders to provide an arc, a magnetic device for shifting one of said holders, a pair of concavo-convex lenses mounted in said tube and spaced from each other, one of said lenses arranged in proximity to the arc, the other of said lenses being colored, and a bi-convex lens mounted in said tube forwardly of said colored lens.

2. A therapeutic device comprising a 115 light casing provided with a light directing tube, inclined carbon holders projecting into said casing, circuit connections leading to said holders, carbons carried by said holders to provide an arc, a magnetic 120 device for shifting one of said holders, a pair of concavo-convex lenses mounted in said tube and spaced from each other, one of said lenses arranged in proximity to the arc, the other of said lenses being colored, 125 and a bi-convex lens mounted in said tube forwardly of said colored lens, said concavo-convex lenses having their concave surfaces opposing said arc.

3. A therapeutic device comprising a 130

light casing provided with a light directing tube, a pair of inclined carbons arranged within and extending in proximity to the forward end of said casing, circuit forming means connected with said carbons, electrically operated means for shifting one of said carbons relatively to the other, a lens carried by the tube and positioned in proximity to the arc formed by said carbons, a colored lens mounted in the tube and spaced from the other lens, said lenses being concavo-convex and having their concave sides opposing the arc, and a bi-convex lens carried by the outer end of the tube and spaced from the colored lens.

4. A therapeutic device comprising a light casing provided with a light directing tube, a pair of inclined carbons arranged

within and extending in proximity to the forward end of said casing, circuit forming 20 means connected with said carbons, electrically operated means for shifting one of said carbons relatively to the other, a lens carried by the tube and positioned in proximity to the arc formed by said carbons, a 25 colored lens mounted in the tube and spaced from the other lens, said lenses being concavo-convex and having their concave sides opposing the arc, and a bi-convex lens carried by the outer end of the tube 30 and spaced from the colored lens, a resistance in circuit with said carbons and arranged exteriorly of the light casing.

In testimony whereof, I affix my signature hereto.

SAMUEL E. PEDEN.
